[57] CLAIM

The ornamental design for a sports car, as shown and described.

DESCRIPTION

FIG. 1 is a perspective view of a sports car made in accordance with the present invention;
FIG. 2 is a side elevational view thereof, the opposite side being a mirror image of that shown;
FIG. 3 is a front elevational view thereof;
FIG. 4 is a rear elevational view thereof;
FIG. 5 is a top plan view thereof; and
FIG. 6 is a partial top plan view of the rear portion thereof with the air foil removed for clarity of illustration.

FIG. 1

FIG. 2

FIG. 3

FIG. 4

FIG. 5

FIG. 6
